US00D332956S

United States Patent [19]

Suda

[11] Patent Number: Des. 332,956

[45] Date of Patent: ** Feb. 2, 1993

[54] NUMERICALLY CONTROLLED DRILLING MACHINE

[75] Inventor: Nobuyuki Suda, Oshino, Japan

[73] Assignee: Fanuc Ltd., Minamitsuru, Japan

[**] Term: 14 Years

[21] Appl. No.: 661,087

[22] Filed: Feb. 26, 1991

[30] Foreign Application Priority Data

Oct. 5, 1990 [JP] Japan 2-33426

[52] U.S. Cl. D15/132

[58] Field of Search D15/132; 29/568; 483/3

CLAIM

The ornamental design for a numerically controlled drilling machine, as shown.

DESCRIPTION

FIG. 1 is a front elevational view of a numerically controlled drilling machine showing my new design;

FIG. 2 is a right side elevational view;

FIG. 3 is a left side elevational view;

FIG. 4 is a rear elevational view;

FIG. 5 is a top plan view;

FIG. 6 is a bottom plan view; and,

FIG. 7 is a perspective view thereof.

FIG. 7 has been drawn on a reduced scale with respect to FIGS. 1-6.

FIG. 1

FIG. 2

FIG. 4

FIG. 3

FIG. 6

FIG. 5

FIG. 7
